U.S. Cl. 260—964 15 Claims

ABSTRACT OF THE DISCLOSURE

Bromoalkyl-(di)-thiolphosphoric acid esters, i.e. O-[(2-bromo-optionally 1 and/or 2-alkyl and/or chloroalkyl)-ethyl and (3-bromo-optionally 1,2 and/or 3-alkyl and/or chloroalkyl)-propyl]-S-[alkyl, chloroalkyl, phenyl, chlorophenyl and alkylphenyl]-[S-(alkyl, alkylmercaptoalkyl, phenyl, chlorophenyl and alkylphenyl) and O-(alkyl and cycloalkyl)]-thiol- and -dithiol-phosphoric acid esters of the formula

in which

R_1 to R_6 , each individually, is hydrogen, alkyl of 1-2 carbon atoms, or chloroalkyl of 1-2 carbon atoms, R_7 is alkyl of 1-4 carbon atoms, chloro atoms, chloro-substituted alkyl of 1-2 carbon atoms, phenyl, chlorophenyl, or alkylphenyl having 1-4 carbon atoms in the corresponding alkyl moiety,

Y is oxygen or sulfur,

R_8 is, when Y is sulfur, alkyl of 1-4 carbon atoms, alkyl-mercapto-alkyl having 1-4 carbon atoms in the alkyl-mercapto moiety and 1-4 carbon atoms in the alkyl moiety, phenyl, chlorophenyl, or alkylphenyl having 1-4 carbon atoms in the corresponding alkyl moiety whereas R_8 is, when Y is oxygen, alkyl of 1-4 carbon atoms or cycloalkyl of 5-6 ring carbon atoms, and

n is 0 or 1,

which possess fungicidal, bactericidal, and arthropodicidal, especially acaricidal and insecticidal, properties.

The present invention relates to and has for its objects the provision for particular new bromoalkyl-(di)-thiolphosphoric acid esters, i.e. O-[(2-bromo-optionally 1 and/or 2-alkyl and/or chloroalkyl)-ethyl and (3-bromo-optionally 1, 2 and/or 3-alkyl and/or chloroalkyl)-propyl]-S-[alkyl, chloroalkyl, phenyl, chlorophenyl and alkylphenyl]-[S-(alkyl, alkylmercaptoalkyl, phenyl, chlorophenyl and alkylphenyl) and O-(alkyl and cycloalkyl)]-thiol- and -dithiol-phosphoric acid esters, which possess fungicidal, bactericidal, and arthropodicidal, especially insecticidal and acaricidal, properties, active compositions in the form of mixtures of such compounds with solid and liquid dispersible carrier vehicles, and methods for producing such compounds and for using such compounds in a new way especially for combating pests, e.g. fungi, bacteria and arthropods, with other and further objects becoming apparent from a study of the within specification and accompanying examples.

In U.S. Pat. 2,690,450, thiolphosphoric acid aryl esters are described which possess parasiticidal, in particular insecticidal, but also fungicidal, properties. From this U.S. Patent, however, it can be learned only that the above-

2

mentioned compounds are suitable as specific fungicides for the control of brown rot (*Sclerotinia fructicola*) and early blight (*Alternaria solani*). There is no indication in said U.S. Pat. 2,690,450 as to whether the products disclosed therein also possess a practical effectiveness against fungal pathogenic agents on rice plants, particularly against the fungus *Piricularia oryzae*.

It has been found, in accordance with the present invention, that the particular new bromoalkyl-(di)-thiolphosphoric acid esters of the formula

in which

R_1 to R_6 , each individually, is hydrogen, alkyl of 1-2 carbon atoms, or chloroalkyl of 1-2 carbon atoms, R_7 is alkyl of 1-4 carbon atoms, chloro-substituted alkyl of 1-2 carbon atoms, phenyl, chlorophenyl, or alkylphenyl having 1-4 carbon atoms in the corresponding alkyl moiety,

Y is oxygen or sulfur,

R_8 is, when Y is sulfur, alkyl of 1-4 carbon atoms, alkyl-mercapto-alkyl having 1-4 carbon atoms in the alkyl-mercapto moiety and 1-4 carbon atoms in the alkyl moiety, phenyl, chlorophenyl, or alkylphenyl having 1-4 carbon atoms in the corresponding alkyl moiety whereas

R_8 is, when Y is oxygen, alkyl of 1-4 carbon atoms or cycloalkyl of 5-6 ring carbon atoms, and n is 0 or 1,

with the provision that at least one of R_7 and R_8 is phenyl, chlorophenyl or alkylphenyl,

exhibit strong fungicidal, bactericidal and arthropodicidal, especially insecticidal and acaricidal, properties.

It has been furthermore found, in accordance with the present invention, that the compounds of Formula I above may be produced by a process which comprises reacting a bromoalkyl-S-alkyl- or -phenyl-thiolphosphoric acid diester chloride of the formula

in which R_1 to R_7 and n are the same as defined above, with an alcohol, mercaptan or thiophenol of the formula

in which Y and R_8 are the same as defined above, or a salt thereof.

Advantageously, the particular new compounds of Formula I above are distinguished by outstanding fungitoxic properties, in particular against fungal pathogenic agents on rice plants. Surprisingly, the instant compounds are in this respect clearly superior to comparable known active compounds of analogous constitution which have already been proposed for the same purpose. In addition, the instant compounds also possess effective bactericidal, insecticidal and acaricidal activity, coupled with low toxicity to warm-blooded creatures and concomitantly low phytotoxicity to higher plants. The new compounds of the present invention therefore represent a genuine enrichment of the art.

If, for example, O-(2-bromoethyl)-S-(methyl)-thiolphosphoric acid diester chloride and thiophenol are used as starting materials, the course of the production process

according to the present invention can be illustrated by the following reaction scheme:

Advantageously, in accordance with the present invention, in the various formulae herein:

R₁ to R₆, each individually, represents

hydrogen;

lower alkyl hydrocarbon of 1-2 carbon atoms such as methyl and ethyl, i.e. C₁₋₂ alkyl, especially methyl; or

chloro-substituted lower alkyl hydrocarbon of 1-2 carbon atoms such as chloromethyl, 2-chloro-ethyl and 1-chloro-ethyl, i.e. chloro-C₁₋₂ alkyl, especially chloromethyl;

R₇ represents

lower alkyl hydrocarbon of 1-4 carbon atoms such as methyl, ethyl, n- and iso-propyl, n-, iso-, sec- and tert.-butyl, and the like, i.e. C₁₋₄ alkyl, especially C₁₋₂ alkyl;

chloro-substituted lower alkyl of 1-2 carbon atoms as defined above, i.e. chloro-C₁₋₂ alkyl, especially 2-chloroethyl;

phenyl;

chlorophenyl such as 2-, 3- and 4-chlorophenyl, especially 2- and 4-chlorophenyl; or

lower alkyl phenyl having 1-4 carbon atoms in the alkyl moiety such as 2-, 3- and 4-methyl, ethyl, n- and iso-propyl, n-, iso-, sec- and tert.-butyl-phenyl, i.e. 2-, 3- and 4-C₁₋₄ alkyl phenyl, especially 2- and 4-C₁₋₄ or C₁₋₂ alkyl phenyl, and more especially 2- and 4-methyl phenyl;

Y represents

oxygen; or

sulfur;

R₈ represents, when Y is sulfur,

lower alkyl hydrocarbon of 1-4 carbon atoms such as methyl to tert.-butyl inclusive, and the like, as defined above, i.e. C₁₋₄ alkyl, especially C₁₋₂ alkyl;

lower alkyl hydrocarbon mercapto-substituted lower alkyl hydrocarbon having 1-4 carbon atoms in the alkylmercapto moiety and 1-4 carbon atoms in the alkyl hydrocarbon moiety such as methyl, ethyl, n- and iso-propyl, n-, iso-, sec- and tert.-butyl, and the like, -mercapto-methyl to tert.-butyl inclusive, as defined above, and the like, i.e. C₁₋₄ alkylmercapto-C₁₋₄ alkyl, especially C₁₋₂ alkylmercapto-C₁₋₂ alkyl, and more especially ethylmercapto-ethyl; phenyl;

chlorophenyl as defined above, especially 2- and 4-chlorophenyl; or

lower alkyl phenyl having 1-4 carbon atoms in the alkyl moiety such as 2-, 3- and 4-methyl to tert.-butyl inclusive, and the like, -phenyl, i.e. 2-, 3- and 4-C₁₋₄ alkyl phenyl, especially 2- and 4-C₁₋₄ or C₁₋₂ alkyl phenyl, and more especially 2- and 4-methyl phenyl; whereas

R₈ represents, when Y is oxygen,

lower alkyl hydrocarbon of 1-4 carbon atoms such as methyl to tert.-butyl inclusive as defined above, and the like, i.e. C₁₋₄ alkyl, especially C₁₋₂ alkyl; or cycloalkyl hydrocarbon of 5-6 ring carbon atoms such as cyclopentyl, cyclohexyl, and the like, i.e. C₅₋₆ cycloalkyl, especially cyclohexyl; and

n represents

a whole number from 0 to 1, preferably 0;

with the proviso that at least one of R₇ and R₈ is such phenyl, chlorophenyl or alkyl phenyl, i.e. R₇ will be

such phenyl, chlorophenyl or alkyl phenyl when Y is oxygen, and R₇ or R₈ or both will be such phenyl, chlorophenyl or alkylphenyl when Y is sulfur.

5 In particular, R₁ is hydrogen, or C₁₋₂ alkyl, especially methyl; R₂ to R₄ and R₆ are hydrogen, or C₁₋₂ alkyl, especially methyl, or chloro-C₁₋₂ alkyl, especially chloromethyl; R₇ is C₁₋₄ or C₁₋₂ alkyl, or chloro-C₁₋₂ alkyl, especially 2-chloroethyl, or phenyl, or chloro-phenyl, especially 2- and 4-chlorophenyl, or C₁₋₄ alkyl-phenyl, especially methylphenyl, more especially 2- and 4-C₁₋₄ alkyl-phenyl, and particularly 2- and 4-methylphenyl; Y is oxygen or sulfur; R₈ is, when Y is sulfur, C₁₋₄ or C₁₋₂ alkyl, or C₁₋₄ alkylmercapto-C₁₋₄ alkyl, especially C₁₋₂ alkylmercapto-C₁₋₂ alkyl, or phenyl, or chlorophenyl, especially 2- and 4-chlorophenyl, or C₁₋₄ alkyl-phenyl, especially methylphenyl, more especially 2- and 4-C₁₋₄ alkyl-phenyl, and particularly 2- and 4-methylphenyl; whereas R₈ is, when Y is oxygen, C₁₋₄ alkyl, especially C₁₋₂ alkyl, or C₅₋₆ cycloalkyl, especially cyclohexyl.

10 Preferably, R₇ is C₁₋₄ alkyl, chloro-C₁₋₂ alkyl, phenyl or chlorophenyl; and R₈ is, when Y is sulfur, C₁₋₄ alkylmercapto-C₁₋₄ alkyl, phenyl, chlorophenyl or C₁₋₄ alkyl phenyl, whereas R₈ is, when Y is oxygen, C₁₋₄ alkyl or C₅₋₆ cycloalkyl.

15 The type of starting alcohols, mercaptans and thiophenols usable in accordance with the process of the present invention are clearly characterized by Formula III above.

20 These starting compounds are well known and can be prepared on an industrial scale.

25 The types of starting bromoalkyl-S-alkyl- or -phenyl-thiolphosphoric acid diester chlorides usable in accordance with the process of the present invention are clearly characterized by Formula II above.

30 Examples of such starting bromo-alkyl-S-alkyl- or -phenyl-thiolphosphoric acid diester chlorides which can be reacted according to the present invention are:

40 O-(2-bromo-ethyl-S-methyl- or S-phenyl-, O-(2-bromo-ethyl)-S-(4'-methyl-phenyl)-, O-(2-bromo-ethyl)-S-(4'-chloro-phenyl)-, O-[3-bromo-butyl-(2)]-S-phenyl-, O-[3-bromo-butyl-(1)]-S-methyl- or S-(4'-methyl-phenyl)-, O-[1,1-dichloro-3-bromo-propyl (2)]-S-(4'-chlorophenyl)-, O-[3-bromo-butyl-(2)]-S-methyl- or S-phenyl-, O-[1-bromo-propyl (2)]-S-methyl- or S-phenyl-, 45 50 O-[1-bromo-propyl-(2)]-S-(4'-chloro-phenyl)- and O-[1-bromo-propyl-(2)]-S-ethyl- or S-(3'-chlorophenyl)-, and the like, -thiolphosphoric acid diester chlorides.

55 The bromoalkyl-S-alkyl- or -phenyl - thiolphosphoric acid diester chlorides of Formula II above usable as starting materials are not yet known from the literature. It has been found that the bromo-alkyl-S-alkyl- or phenyl-thiolphosphoric acid diester chlorides concerned are obtained with very good yields as well as in outstanding purity by precursor reaction of equimolar amounts of 2-chloro-phospholanes or 2-chloro-phosphorinanes of the formula

with aliphatic or aromatic sulfenic acid bromides of the formula

In the aforesaid Formulae IV and V, R_1 to R_7 and n are the same as defined above.

The precursor reaction can be carried out in the presence or absence of solvents or diluents such as (optionally chlorinated) aliphatic and aromatic hydrocarbons, ethers or low-molecular-weight ketones and nitriles; and the like, at temperatures of substantially between about -20 to $+50$, preferably at between about -10 to $+30^\circ C$.

It is preferable to add the sulfenic acid bromide (possibly diluted with one of the above-mentioned solvents) dropwise to the solution or suspension of the phospholane or phosphorinane derivative at a temperature within the above-mentioned range with stirring and possible cooling of the reaction mixture. After completion of the addition, the mixture is left to stand for about 1 to 3 hours to complete the reaction, the solvent is then drawn off and the residue may be subjected to fractional distillation under reduced pressure. In most cases, however, with the described method of working, the starting materials are obtained in such high purity that their further reaction is possible without purification.

According to a particular embodiment of the process of the present invention, isolation of the bromoalkyl-S-alkyl- or -phenyl-thiolphosphoric acid diester chlorides concerned is dispensed with entirely and, instead, the reaction products of the above-mentioned 2-chloro-phospholanes or -phosphorinanes with the appropriate sulfenic acid bromides are immediately reacted in a "one-pot" process with the required alcohol, mercaptan or thiophenol of Formula III above.

The process according to the present invention can also be carried out in the presence of solvent or diluents. As such, practically all inert organic solvents are suitable. Particularly good results, however, have been obtained with (optionally chlorinated) aliphatic and aromatic hydrocarbons, such as methylene chloride, dichloroethane, di-, tri- and tetrachloroethylene, chloroform, carbon tetrachloride, benzine, benzene, chlorobenzene, toluene and xylene; ethers, for example diethyl and di-n-butyl ether, dioxan, tetrahydrofuran or low-molecular-weight aliphatic ketones or nitriles, for example acetone, methylethyl ketone, methylisopropyl ketone and methylisobutyl ketone, acetonitrile and propionitrile; and the like.

Furthermore, the alcohols, mercaptans and thiophenols to be reacted according to the present process can be reacted in the form of their salts, preferably the appropriate alkali metal or ammonium salts. It is alternatively possible to work the process in the presence of acid-binding agents. As the latter, the usual acid acceptors are suitable, such as alkali metal carbonates, alcoholates and hydroxides, for example potassium and sodium carbonate, methylate, ethylate and hydroxide, as well as tertiary aliphatic, aromatic or heterocyclic bases, such as triethylamine, dimethylaniline, benzylidemethylamine or pyridine; and the like.

The reaction temperatures in the case of the process according to the present invention can be varied within a fairly wide range. In general, the reaction is carried out at substantially between about 20 – $100^\circ C$. (or the boiling point of the mixture), preferably at between about 25 – $80^\circ C$.

For the carrying out of the instant process there is theoretically necessary—as can be seen from the above reaction equation—1 mol of alcohol, mercaptan or thiophenol per mol of bromoalkyl-S-alkyl- or phenyl-thiolphosphoric acid diester chloride. Usually, equimolar amounts of the starting materials are employed, but an excess of the second reaction component can sometimes be advantageous. It has proved expedient either to add dropwise, with stirring, the bromoalkyl-S-alkyl- or -phenyl-

thiolphosphoric acid diester chloride to the solution or suspension of the alcohol, mercaptan or thiophenol in one of the above-mentioned solvents or, conversely, to add the appropriate hydroxyl- or sulfohydryl-group-containing compound of Formula III above to the diester chloride (or to the reaction product of the appropriate 2-chloro phospholane or -phosphorinane derivative with the particular sulfenic acid bromide).

After mixing the starting components, the reaction mixture is, in order to complete the reaction, left to stand for some time (for example 1 to 3 hours) and/or heated at the above-mentioned temperatures until the reaction is complete, for example for several hours (or overnight), with stirring.

15 The working up of the mixture may take place, in known manner, by pouring the mixture into ice water, optionally deacidifying the solution, taking up the separated reaction product (in most cases in oily form) in a water-immiscible solvent, preferably one of the above-mentioned hydrocarbons, for example benzene, washing the organic layer until there is a neutral reaction, separation of the phases, drying of the solution, distilling off the solvent and, if possible, fractional distillation of the residue under reduced pressure.

20 25 The instant compounds are obtained in most cases in the form of colorless to slightly yellow-colored viscous oils, some of which can be distilled under greatly reduced pressure without decomposition. When this is not possible, the compounds obtained can, for purification, be "slightly 30 distilled," that is freed from the last volatile impurities by longer heating to slightly to moderately elevated temperatures in a vacuum.

Surprisingly, the instant new compounds when compared to the closest active compounds of analogous constitution and the same type of activity previously known from the literature are distinguished by a substantially better bactericidal, insecticidal, acaricidal, but especially fungicidal, effectiveness, as well as a repellent effect against destructive birds, with only slight toxicity to warm-blooded animals and only slight phytotoxicity. The effect sets in rapidly and is long-lasting.

35 By reason of their above-mentioned properties, the instant new compounds can be used with success in plant protection endeavors, especially against a multiplicity of the most diverse plant and animal parasites, such as fungi, sucking and eating insects, Diptera and mites.

40 45 The instant new active compounds exhibit an especially strong fungitoxic activity against phytopathogenic fungi. Likewise, diseases caused by bacteria can be controlled with these compounds. The good compatibility with warm-blooded animals and with higher plants permits the use of such compounds as plant protection agents against fungal diseases. In the concentrations necessary for the control of fungi, the instant compounds do not damage cultivated plants.

50 55 Fungitoxic agents in plant protection are used for the control of fungi from the most diverse classes of fungi, such as Archimycetes, Phycomycetes, Ascomycetes, Basidiomycetes and *Fungi imperfecti*.

60 The instant active compounds possess a broad spectrum of activity. They can be used against parasitic fungi on above-the-soil parts of plants, fungi which cause tracheomycosis, fungi which attack the plants from the soil and seed-borne as well as soil-inhabiting fungi.

65 70 75 The instant new compounds have given particularly good results in the control of rice diseases. Such compounds show an excellent activity against the fungi *Piricularia oryzae* and *Pellicularia sasakii*, by reason of which they may be used for the joint control of these two diseases. This represents a substantial advance in the art, since up to now agents of different chemical constitution were individually necessary to combat and control these two fungi, respectively. Surprisingly, the instant active compounds show not only a protective activity, but also a curative effect.

However, the instant new compounds also act against other fungi which infest rice or other cultivated plants, such as *Cochliobolus miyabeanus*, *Mycosphaerella muscicola*, *Cercospora personata*, *Botrytis cinerea* and *Alternaria* species, *Fusarium* species, *Verticillium alboatrium* and *Phialophora cinerescens*; and the like.

The active compounds according to the instant invention can be utilized, if desired, in the form of the usual pesticidal diluents or extenders, i.e. conventional pesticidal dispersible carrier vehicles such as solutions, emulsions, suspensions, emulsifiable concentrates, spray powders, pastes, soluble powders, dusting agents, granules, etc. These are prepared in known manner, for instance by extending the active compounds with conventional pesticidal dispersible liquid diluent carriers and/or dispersible solid carriers optionally with the use of carrier vehicle assistants, e.g. conventional pesticidal surface-active agents, including emulsifying agents and/or dispersing agents, whereby, for example, in the case where water is used as diluent, organic solvents may be added as auxiliary solvents. The following may be chiefly considered for use as conventional carrier vehicles for this purpose: inert dispersible liquid diluent carriers, including inert organic solvents, such as aromatic hydrocarbons (e.g. benzene, toluene, xylene, etc.), halogenated, especially chlorinated, aromatic hydrocarbons (e.g. chlorobenzenes, etc.), paraffins (e.g. petroleum fractions), chlorinated aliphatic hydrocarbons (e.g. methylene chloride, etc.), alcohols (e.g. methanol, ethanol, propanol, butanol, etc.), amines (e.g. ethanolamine, etc.), ethers, ether-alcohols (e.g. glycol monomethyl ether, etc.), amides (e.g. dimethyl formamide, etc.), sulfoxides (e.g. dimethyl sulfoxide, etc.), ketones (e.g. acetone, etc.) and/or water; as well as inert dispersible finely divided solid carriers, such as ground natural minerals (e.g. kaolins, alumina, silica, chalk, i.e. calcium carbonate, talc, kieselguhr, etc.) and ground synthetic minerals (e.g. highly dispersed silicic acid, silicates, e.g. alkali silicates, etc.); whereas the following may be chiefly considered for use as conventional carrier vehicle assistant, e.g. surface-active agents, for this purpose: emulsifying agents, such as non-ionic and/or anionic emulsifying agents (e.g. polyethylene oxide esters of fatty acids, polyethylene oxide ethers of fatty alcohols, alkyl sulfonates, aryl sulfonates, etc., and especially alkyl aryl-polyglycol ethers, magnesium stearate, sodium oleate, etc.); and/or dispersing agents, such as lignin, sulfite waste liquors, methyl cellulose, etc.

Such active compounds may be employed alone or in the form of mixtures with one another and/or with such solid and/or liquid dispersible carrier vehicles and/or with other known compatible active agents, especially plant protection agents, such as other acaricides, insecticides, fungicides, or bactericides, or herbicides, etc., if desired, or in the form of particular dosage preparations for specific application made therefrom, such as solutions, emulsions, suspensions, powders, pastes, and granules which are thus ready for use.

As concerns commercially marketed preparations, these generally contemplate carrier composition mixtures in which the active compound is present in an amount substantially between about 0.1-95% by weight, and preferably 0.5-90% by weight, of the mixture, whereas carrier composition mixtures suitable for direct application or field application generally contemplate those in which the active compound is present in an amount substantially between about 0.0001-10%, preferably 0.01-1%, by weight of the mixture. Thus, the present invention contemplates overall compositions which comprise mixtures of a conventional dispersible carrier vehicle such as (1) a dispersible inert finely divided carrier solid, and/or (2) a dispersible carrier liquid such as an inert organic solvent and/or water preferably including a surface-active effective amount of a carrier vehicle assistant, e.g. a surface-active agent, such as an emulsifying agent and/or a dispersing agent, and an amount of the active compound

which is effective for the purpose in question and which is generally between about 0.0001-95%, and preferably 0.01-95%, by weight of the mixture.

The active compounds can also be used in accordance with the well known ultra-low-volume process with good success, i.e. by applying such compound if normally a liquid, or by applying a liquid composition containing the same, via very effective atomizing equipment in finely divided form, e.g. average particle diameter of from 50-100 microns, or even less, i.e. mist form, for example by airplane crop spraying techniques. Only up to at most about a few liters/hectare are needed, and often amounts only up to about 1 quart/acre, preferably 2-16 fluid ounces/acre, are sufficient. In this process it is possible to use highly concentrated liquid compositions with said liquid carrier vehicles containing from about 20 to about 95% by weight of active compound or even the 100% active substance alone, e.g. about 20-100% by weight of the active compound.

In particular, the present invention contemplates methods of selectively killing, combating or controlling pests, e.g. fungi, bacteria or arthropods, i.e. insects and acarids, and more particularly, methods of combating at least one of fungi, bacteria, insects and acarids which comprises applying to at least one of correspondingly (a) such pests, i.e. fungi, bacteria, insects or acarids, and (b) the corresponding habitat, i.e. the locus to be protected, a correspondingly combative or toxic amount, i.e. a fungicidally, bactericidally or arthropodically, especially insecticidally or acaricidally, effective amount of the particular active compound of the invention alone or together with a carrier vehicle as noted above. The instant formulations or compositions are applied in the usual manner, for instance by spraying, atomizing, vaporizing, scattering, dusting, watering, sprinkling, pouring, squirting, fumigating, incrustations, dressings, and the like.

It will be realized, of course, that the concentration of the particular active compound utilized in admixture with the carrier vehicle will depend upon the intended application. Therefore, in special cases it is possible to go above or below the aforementioned concentration ranges.

The unexpected superiority and outstanding activity of the particular new compounds of the present invention is illustrated without limitation by the following examples:

EXAMPLE 1

Piricularia test: liquid preparation of active compound

Solvent: 4 parts by weight acetone

Dispersing agent: 0.05 part by weight sodium oleate

Other additive: 0.2 part by weight gelatin

Water: 95.75 parts by weight

The amount of the particular active compound required for the desired concentration of such active compound in the spray liquor is mixed with the stated amount of solvent, and the resulting concentrate is diluted with the stated amount of water containing the stated dispersive agent and other additive.

Test for protective action

30 rice plants about 14 days old are sprayed (i.e. treated) with the active compound-containing spray liquor until dripping wet. The plants remain in a greenhouse at temperatures of 22 to 24° C. and a relative atmospheric humidity of about 70% until the plants are dry. The plants are then inoculated with an aqueous suspension of 100,000 to 200,000 spores/ml. of *Piricularia oryzae* and placed in a chamber at 24-26° C. and 100% relative atmospheric humidity.

5 days after inoculation, the infestation of all the leaves present at the time of inoculation is determined as a percentage of the untreated but also inoculated control plants. 0% means no infestation; 100% means that the infestation is exactly as great as in the case of the control plants.

The particular active compounds tested, their concentrations and the results obtained can be seen from the following Table 1:

Test for curative action

The above test shows the protective effect of the active compounds. In order to show the curative effect, a similar test is carried out on some of the active compounds with the difference that the active compounds are applied not before, but only after 16 hours after, inoculation. Substances which show an activity when the test is conducted in this manner are capable of killing the fungus after infection and therefore can exercise a curative action. The results of this test are also shown in Table 1.

EXAMPLE 2

Myzus test (contact action)

Solvent: 3 parts by weight acetone

Emulsifier: 1 part by weight alkylaryl polyglycol ether

To produce a suitable preparation of the particular active compound, 1 part by weight of such active compound is mixed with the stated amount of solvent containing the stated amount of emulsifier and the resulting concentrate is diluted with water to the desired final concentration.

Cabbage plants (*Brassica oleracea*) which have been heavily infested with peach aphids (*Myzus persicae*) are sprayed with the preparation of the given active compound until dripping wet.

After the specified period of time, the degree of destruction is determined as a percentage: 100% means that all the aphids are killed whereas 0% means that none of the aphids are killed.

The particular active compounds tested, their concentrations, the evaluation time and the results obtained can be seen from the following Table 2:

TABLE 2
[Myzus test]

Active compound	Concentration of active compound in percent	Degree of destruction in percent after 24 hours
(9) ...	0.1 0.01	100 96

EXAMPLE 3

Tetranychus test

Solvent: 3 parts by weight acetone

Emulsifier: 1 part by weight alkylaryl polyglycol ether

To produce a suitable preparation of the particular active compound, 1 part by weight of such active compound is mixed with the stated amount of solvent containing the stated amount of emulsifier and the resulting concentrate is diluted with water to the desired final concentration.

Bean plants (*Phaseolus vulgaris*), which have a height of approximately 10-30 cm., are sprayed with the preparation of the given active compound until dripping wet. These bean plants are heavily infested with spider mites (*Tetranychus telarius*) in all stages of development.

After the specified period of time, the effectiveness of the given active compound preparation is determined by counting the dead mites. The degree of destruction thus obtained is expressed as a percentage. 100% means that all the spider mites are killed whereas 0% means that none of the spider mites are killed.

The particular active compounds tested, their concen-

trations, the evaluation time and the results obtained can be seen from the following Table 3:

TABLE 3
[Tetranychus test]

Active compound	Concentration of active compound in percent	Degree of destruction in percent after 48 hours
(9a) ...	0.1	99
(15a) ...	0.1	100

EXAMPLE 4

Bombyx test

Solvent: 3 parts by weight acetone

Emulsifier: 1 part by weight alkylaryl polyglycol ether

To produce a suitable preparation of the particular active compound, 1 part by weight of such active compound is mixed with the stated amount of solvent containing the stated amount of emulsifier, and the resulting concentrate is diluted with water to the desired final concentration.

20 Mulberry leaves (*Morus alba*) are sprayed with this preparation of the given active compound until dew-moist and are then infested with caterpillars of the silk moth (*Bombyx mori*).

25 After the period of time stated below, the degree of destruction is determined as a percentage. 100% means that, 0% means that no, caterpillars were killed.

30 The particular active compounds tested, their concentrations, the evaluation time and the results obtained can be seen from the following Table 4:

TABLE 4
[Bombyx test]

Active compound	Concentration of active compound in percent	Degree of destruction in percent after 3 days
(12a) ...	0.1	100
(16a) ...	0.1	100
(20a) ...	0.1	90
(3a) ...	0.1	100
(13a) ...	0.1	100
(11a) ...	0.1	100
(17a) ...	0.1 0.01 0.001	100 100 40

TABLE 4—Continued

Active compound	Concentration of active compound in percent	Degree of destruction in percent after 3 days
(6a)...	0.1	100

The following further examples illustrate, without limitation, the process for producing the particular new compounds of the present invention:

EXAMPLE 5

0.5 mol methylsulfuric acid bromide is added, at 10 to 20° C., to a solution of 63 g. (0.5 mol) 2-chlorodioxaphospholane-1,3,2 in 100 ml. chloroform, the solvent is then evaporated off, and the residue is distilled. The yield is 74 g. (58% of the theory).

The O-(2-bromo-ethyl)-S-methyl-thiolphosphoric acid diester chloride boils at 130° C. under a pressure of 2 mm. Hg.

44 g. thiophenol and 41 g. triethylamine in 100 ml. benzene are added, at 30 to 40° C., to 0.4 mol O-(2-bromo-ethyl)-S-methyl-thiolphosphoric acid diester chloride dissolved in 300 ml. benzene. The mixture is subsequently stirred for three hours, then washed, dried and slightly distilled. The yield of O-(2-bromo-ethyl)-S-methyl-S-phenyl-dithiolphosphoric acid ester is 104 g. (80% of the theory), refractive index $n_D^{23}=1.6023$.

Analysis.— $C_9H_{12}BrO_2PS_2$ (molecular weight 327). Calculated (percent): P, 9.5; S, 19.6; Br, 24.6. Found (percent): P, 9.4; S, 19.15; Br, 23.18.

EXAMPLE 6

Preparation takes place in analogy with Example 5 (a), but with the use of 2-chloro-4-methyl-dioxaphospholane-1,3,2.

The yield is 87% of the theory.

58 g. 4-chloro-thiophenol and 41 g. triethylamine are added to a solution of 107 g. O-[3-bromopropyl-(2)]-S-methyl-thiolphosphoric acid diester chloride in 500 cc. benzene; the reaction mixture is subsequently stirred for 2 hours, then washed, dried, and slightly distilled under a vacuum produced by a mercury pump.

The yield of O-(1-bromo-prop-2-yl)-S-methyl-S-(4'-chloro-phenyl)-dithiolphosphoric acid ester is 69% of the theory, the refractive index $n_D^{23}=1.5931$.

Analysis.— $C_{19}H_{13}BrClO_2PS_2$ (molecular weight 376).

Calculated (percent): Cl, 9.75; Br, 21.2; P, 8.3. Found (percent): Cl, 10.10; Br, 20.3; P, 8.3.

EXAMPLE 7

Preparation takes place in manner analogous with that in Example 5(a), but using 2-chloro-4,5-dimethyldioxaphospholane-1,3,2.

Yield: 80% of the theory.

25 g. 4-thiocresol and 21 g. triethylamine, dissolved in 100 ml. benzene, are added, at 20 to 30° C., to 56 g. O-[3-bromo-butyl-(2)]-S-methyl-thiolphosphoric acid diester chloride in 300 ml. benzene. The mixture is subsequently stirred for 2 hours, then washed, dried and slightly distilled.

The yield of O-(3-bromo-but-2-yl)-S-methyl-S-(4'-methyl-phenyl)-dithiolphosphoric acid ester is 84% of the theory, the refractive index $n_D^{23}=1.5747$.

Analysis.— $C_{12}H_{18}BrO_2PS_2$ (molecular weight 369). Calculated (percent): S, 17.3; P, 8.4. Found (percent): S, 17.65; P, 9.0.

EXAMPLE 8

Preparation is effected in analogy with Example 5(a), but with the use of 2-chloro-4-methyl-1,3,2-dioxaphosphorinane.

Yield: 81% of the theory.

A mixture of 33 g. thiophenol and 31 g. triethylamine in 100 ml. benzene is added, at 20 to 30° C., to 85 g. O-[4-bromo-butyl-(2)]-S-methyl-thiolphosphoric acid diester chloride in 300 ml. benzene. The reaction mixture is subsequently stirred for 3 hours, then washed, dried and slightly distilled.

The yield of O-(4-bromo-but-2-yl)-S-methyl-S-phenyl-dithiophosphoric acid ester is 69% of the theory, the refractive index $n_D^{23}=1.5798$.

Analysis.— $C_{11}H_{16}BrO_2PS_2$ (molecular weight 355). Calculated (percent): S, 18.0; P, 8.7. Found (percent): S, 17.1; P, 9.6.

17

EXAMPLE 9

Preparation takes place as in Example 5(a), but using 2-chloro-4-chloromethyl-1,3,2-dioxaphospholane.

Yield: 87% of the theory.

33 g. thiophenol and 31 g. triethylamine in 100 ml. benzene are added, at 20 to 30° C., to 91 g. O-[1-chloro-3-bromo-propyl - (2)]-S-methylthiophosphoric acid diester chloride dissolved in 300 ml. benzene. The mixture is subsequently stirred for three hours, then washed, dried and slightly distilled.

The yield of O-(1-bromo-3-chloro-prop-2-yl)-S-methyl-S-phenyl-dithiophosphoric acid ester is 66% of the theory, the refractive index $n_D^{23}=1.5958$.

Analysis.— $C_{10}H_{13}BrClO_2PS_2$ (molecular weight 376). Calculated (percent): Cl, 9.4; S, 17.0; P, 8.3. Found (percent): Cl, 9.67; S, 16.19; P, 8.58.

EXAMPLE 10

Preparation takes place in analogy with Example 5(a), but using ethylsulfenic acid bromide.

The yield is 89% of the theory.

36 g. 4-chloro-thiophenol and 26 g. triethylamine in 100 ml. benzene are added, at 30 to 35° C., to 69 g. O-(2-bromo-ethyl) - S - ethyl-thiophosphoric acid diester chloride. The mixture is subsequently stirred for three hours, then washed, dried and slightly distilled.

Yield: 85% of the theory of O-(2-bromo-ethyl)-S-ethyl-S-(4'-chloro-phenyl)-dithiophosphoric acid ester, refractive index $n_D^{23}=1.5966$.

Analysis.— $C_{10}H_{13}BrClO_2PS_2$ (molecular weight 376). Calculated (percent): Cl, 9.5; S, 17.0; P, 8.3. Found (percent): Cl, 9.54; S, 17.12; P, 8.36.

EXAMPLE 11

Preparation takes place in manner analogous with that of Example 5(a), but with 2-chloro-ethylsulfenic acid bromide and 2 - chloro-4 - methyl - 1,3,2 - dioxaphospholane.

22 g. thiophenol and 21 g. triethylamine in 100 ml. benzene are added, at 20 to 30° C., to a solution of 63 g. O-[3-bromo-propyl - (2)] - S - (2'-chloro-ethyl)-thiophosphoric acid diester chloride in 300 ml. benzene; the reaction mixture is subsequently stirred for 2 hours, then washed, dried and slightly distilled.

The yield of O-(1 - bromo-prop - 2-yl)-S-(2'-chloro-

18

ethyl)-S-phenyl-dithiophosphoric acid ester is 77% of the theory, the refractive index $n_D^{22}=1.5836$.

Analysis.— $C_{11}H_{15}BrClO_2PS_2$ (molecular weight 390). Calculated (percent): Cl, 9.1; P, 7.95. Found (percent): Cl, 8.44; P, 7.87.

EXAMPLE 12

Preparation takes place in analogy with Examples 5(a), but with the use of phenylsulfenic acid bromide.

Yield: 88% of the theory.

63 g. O-(2-bromoethyl)-S-phenyl-thiophosphoric acid diester chloride are dissolved in 300 ml. benzene, and to this solution there is added, at 20 to 25° C., a mixture of 22 g. thiophenol and 21 g. triethylamine in 100 ml. benzene. The reaction mixture is subsequently stirred for 3 hours, then washed, dried and slightly distilled.

The yield of O-(2-bromo-ethyl)-S,S-diphenyl-dithiophosphoric acid ester is 75% of the theory, the refractive index $n_D^{22}=1.6140$.

Analysis.— $C_{14}H_{14}BrO_2PS_2$ (molecular weight 389). Calculated (percent): S, 16.5; P, 8.0. Found (percent): S, 17.1; P, 7.6.

EXAMPLE 13

Preparation takes place in analogy with Example 5(a), but with phenylsulfenic acid bromide and 2-chloro-4-methyl-1,3,2-dioxaphospholane.

Yield: 94% of the theory.

13 g. methanol and 41 g. triethylamine in 100 ml. benzene are added, at 20 to 25° C., to a solution of 132 g. O-[3-bromo-propyl-(2)]-S-phenyl-thiophosphoric acid diester chloride in 400 ml. benzene; the reaction mixture is subsequently stirred for 3 hours, then washed, dried and slightly distilled.

The yield of O-(1-bromo-prop-2-yl)-O-methyl-S-phenyl-thiophosphoric acid ester is 72% of the theory, the refractive index is $n_D^{22}=1.5717$.

Analysis.— $C_{10}H_{14}BrO_3PS$ (molecular weight 325). Calculated (percent): P, 9.55. Found (percent): P, 8.90.

In analogous manner, the following compounds can be prepared:

Yield: 83% of the theory of O-(2-bromo-ethyl)-S-phenyl-S-(4'-chloro-phenyl)-dithiophosphoric acid ester, refractive index $n_D^{23}=1.6278$.

19

Analysis. — $C_{14}H_{13}BrClO_2PS_2$ (molecular weight 424). Calculated (percent): S, 15.1; P, 7.3. Found (percent): S, 15.9; P, 6.9.

Yield: 85% of the theory of O-(2-bromo-ethyl)-S-phenyl-S-(2'-methyl-phenyl)-dithiolphosphoric acid ester, refractive index $n_D^{23}=1.6180$.

Analysis. — $C_{15}H_{16}BrO_2PS_2$ (molecular weight 403). Calculated (percent): S, 15.9; P, 7.7. Found (percent): S, 16.8; P, 7.73.

Yield: 73% of the theory of O-(1-bromo-prop-2-yl)-S-phenyl-S-(4'-chlorophenyl)-dithiolphosphoric acid ester, refractive index $n_D^{23}=1.6342$.

Analysis. — $C_{15}H_{15}BrClO_2PS_2$ (molecular weight 438). Calculated (percent): Cl, 8.1; P, 7.1. Found (percent): Cl, 8.12; P, 6.6.

Yield: 80% of the theory of O-(2-bromo-ethyl)-S-methyl-S-(4'-chlorophenyl)-dithiolphosphoric acid ester, refractive index $n_D^{23}=1.6064$.

Analysis. — $C_9H_{11}BrClO_2PS_2$ (molecular weight 362). Calculated (percent): S, 17.7; P, 8.6. Found (percent): S, 17.4; P, 8.6.

Yield: 75% of the theory of O-(2-bromo-ethyl)-S-methyl-S-(2'-methyl-phenyl)-dithiolphosphoric acid ester, refractive index $n_D^{23}=1.5951$.

Analysis. — $C_{10}H_{14}BrO_2PS_2$ (molecular weight 341). Calculated (percent): S, 18.8; P, 9.1. Found (percent): S, 18.5; P, 9.2.

Yield: 72% of the theory of O-(1-bromo-prop-2-yl)-S-methyl-S-(2'-chlorophenyl)-dithiolphosphoric acid ester, refractive index $n_D^{23}=1.5888$.

Analysis. — $C_{10}H_{13}BrClO_2PS_2$ (molecular weight 376). Calculated (percent): S, 17.0; P, 8.25. Found (percent): S, 16.4; P, 7.96.

Yield: 75% of the theory of O-(1-bromo-prop-2-yl)-S-methyl-S-phenyl dithiolphosphoric acid ester, refractive index $n_D^{23}=1.5870$.

Analysis. — $C_{10}H_{14}BrO_2PS_2$ (molecular weight 341). Calculated (percent): P, 9.1. Found (percent): P, 9.64.

20

Yield: 74% of the theory of O-(1-bromo-prop-2-yl)-S-methyl-S-(4'-methyl-phenyl)-dithiolphosphoric acid ester, refractive index $n_D^{23}=1.5823$.

Analysis. — $C_{11}H_{16}BrO_2PS_2$ (molecular weight 355). Calculated (percent): P, 8.7. Found (percent): 8.98.

Yield: 60% of the theory of O-(3-bromo-but-2-yl)-S-phenyl-dithiolphosphoric acid ester, refractive index $n_D^{25}=1.5656$.

Analysis. — $C_{11}H_{16}BrO_2PS_2$ (molecular weight 355). Calculated (percent): P, 8.75. Found (percent): P, 9.5.

Yield: 82% of the theory of O-(1-bromo-but-3-yl)-S-methyl-S-(4'-chlorophenyl)dithiolphosphoric acid ester, refractive index $n_D^{23}=1.5829$.

Analysis. — $C_{11}H_{15}BrClO_2PS_2$ (molecular weight 390). Calculated (percent): P, 7.95. Found (percent): P, 8.56.

Yield: 72% of the theory of O-(1-bromo-3-chloroprop-2-yl) - S - methyl-S-(4'-chlorophenyl) - dithiolphosphoric acid ester, refractive index $n_D^{23}=1.5993$.

Analysis. — $C_{10}H_{12}BrCl_2O_2PS_2$ (molecular weight 410). Calculated (percent): P, 7.6. Found (percent): P, 7.55.

Yield: 86% of the theory of O-(2-bromo-ethyl)-S-ethyl-S-phenyl-dithiolphosphoric acid ester, refractive index $n_D^{23}=1.5880$.

Analysis. — $C_{10}H_{14}BrO_2PS_2$ (molecular weight 341). Calculated (percent): S, 18.8; P, 9.1. Found (percent): S, 18.12; P, 9.17.

Yield: 74% of the theory of O-(1-bromo-prop-2-yl)-S-(2'-chloro-ethyl) - S - (4''-chlorophenyl) - dithiolphosphoric acid ester, refractive index $n_D^{23}=1.6000$.

Analysis. — $C_{11}H_{14}BrCl_2O_2PS_2$ (molecular weight 424). Calculated (percent): Cl, 16.8; S, 15.1; P, 7.3. Found (percent): Cl, 16.74; S, 15.9; P, 6.74.

Yield: 80% of the theory of O-(1-bromo-prop-2-yl)-S-ethyl-S-phenyl-dithiolphosphoric acid ester, refractive index $n_D^{20}=1.5777$.

21

Analysis.— $C_{11}H_{16}BrO_2PS_2$ (molecular weight 355). Calculated (percent): S, 18.0; P, 8.75. Found (percent): S, 17.74; P, 9.16.

Yield: 79% of the theory of O-(1-bromo-prop-2-yl)-S-n-butyl-S-phenyl-dithiophosphoric acid ester, refractive index $n_D^{21}=1.5670$.

Analysis.— $C_{13}H_{20}BrO_2PS_2$ (molecular weight 383). Calculated (percent): S, 16.7; P, 8.1. Found (percent): S, 16.55; P, 8.21.

Yield: 53% of the theory of O-(1-bromo-prop-2-yl)-S-isopropyl-S-phenyl-dithiophosphoric acid ester, refractive index $n_D^{21}=1.5691$.

Analysis.— $C_{12}H_{18}BrO_2PS_2$ (molecular weight 369). Calculated (percent): S, 17.35; P, 8.4. Found (percent): S, 16.17; P, 8.8.

Yield: 88% of the theory of O-(1-bromo-prop-2-yl)-S-(2'-ethylmercapto-ethyl)-S-phenyl-dithiophosphoric acid ester, refractive index $n_D^{21}=1.5840$.

Analysis.— $C_{13}H_{20}BrO_2PS_3$ (molecular weight 415). Calculated (percent): S, 23.1; P, 7.5. Found (percent): S, 23.3; P, 7.21.

Yield: 55% of the theory of O-(1-bromo-prop-2-yl)-O-ethyl-S-phenyl-thiolphosphoric acid ester, refractive index $n_D^{20}=1.5586$.

Analysis.— $C_{11}H_{16}BrO_3PS$ (molecular weight 339). Calculated (percent): S, 9.4; P, 9.1. Found (percent): S, 8.96; P, 9.29.

Yield: 80% of the theory of O-(1-bromo-prop-2-yl)-O-ethyl-S-(4'-chlorophenyl)-thiolphosphoric acid ester, refractive index $n_D^{23}=1.5576$.

Analysis.— $C_{11}H_{15}BrClO_3PS$ (molecular weight 374). Calculated (percent): Cl, 9.5; P, 8.3. Found (percent): Cl, 8.86; P, 8.58.

Yield: 66% of the theory of O-(2-bromo-ethyl)-O-cyclohexyl-S-phenyl-thiolphosphoric acid ester, refractive index $n_D^{23}=1.5619$.

22

Analysis.— $C_{14}H_{20}BrO_3PS$ (molecular weight 379). Calculated (percent): P, 8.2. Found (percent): P, 7.4.

Yield: 68% of the theory of O-(2-bromo-ethyl)-O-ethyl-S-(4'-chlorophenyl)-thiolphosphoric acid ester, refractive index $n_D^{23}=1.5560$.

Analysis.— $C_{10}H_{13}BrClO_3PS$ (molecular weight 360). Calculated (percent): P, 8.6; Cl, 9.8. Found (percent): P, 8.47; Cl, 9.81.

It will be realized that all of the foregoing compounds contemplated by the present invention possess the desired strong and selective pesticidal, especially fungicidal, bactericidal and arthropodicidal, i.e. insecticidal or acaricidal, properties, with regard to a broad spectrum of activity for combating correspondingly fungi, bacteria, insects and acarids, and that such compounds have not only a very slight toxicity toward warm-blooded creatures, but also a concomitantly low phytotoxicity to higher plants.

As may be used herein, the terms "arthropod," "arthropodicidal" and "arthropodicide" contemplate specifically both insects and acarids. Thus, the insects and acarids may be considered herein collectively as arthropods to be combated in accordance with the invention, and accordingly the insecticidal and/or acaricidal activity may be termed arthropodicidal activity, and the concomitant combative or effective amount used will be an arthropodicidally effective amount which in effect means an insecticidally or acaridically effective amount of the active compound for the desired purposes.

It will be appreciated that the instant specification and examples are set forth by way of illustration and not limitation, and that various modifications and changes may be made without departing from the spirit and scope of the present invention.

What is claimed is:

1. Bromoalkyl-(di)-thiol-phosphoric acid esters of the formula

in which R_1 to R_6 , each individually is selected from the group consisting of hydrogen, alkyl of 1-2 carbon atoms, and chloro-substituted alkyl of 1-2 carbon atoms; R_7 is selected from the group consisting of alkyl of 1-4 carbon atoms, chloro-substituted alkyl of 1-2 carbon atoms, phenyl, chlorophenyl, and alkyl-phenyl having 1-4 carbon atoms in the alkyl moiety; R_8 is selected from the group consisting of alkyl of 1-4 carbon atoms, alkylmercapto-alkyl having 1-4 carbon atoms in the alkylmercapto moiety and 1-4 carbon atoms in the alkyl moiety, phenyl, chlorophenyl, and alkyl-phenyl having 1-4 carbon atoms in the alkyl moiety with the proviso that at least one of R_7 and R_8 is selected from the group consisting of said phenyl, chlorophenyl and alkyl-phenyl.

2. Ester according to claim 1 wherein R_1 is selected from the group consisting of hydrogen and C_{1-2} alkyl; R_2 to R_4 and R_6 are hydrogen; R_5 is selected from the group consisting of hydrogen, C_{1-2} alkyl and chloro- C_{1-2} alkyl; R_7 is selected from the group consisting of C_{1-4} alkyl, chloro- C_{1-2} alkyl, phenyl, chlorophenyl and C_{1-4} alkyl-phenyl; R_8 is selected from the group consisting of C_{1-4} alkyl, C_{1-4} alkylmercapto- C_{1-4} alkyl, phenyl, chlorophenyl and C_{1-4} alkyl-phenyl; and n is 0-1; with the proviso that at least one of R_7 and R_8 is selected from the group consisting of said phenyl, chlorophenyl and C_{1-4} alkyl-phenyl.

3. Ester according to claim 1 wherein R_1 is selected from the group consisting of hydrogen and methyl; R_2 to R_4 and R_6 are hydrogen; R_5 is selected from the group consisting of hydrogen, methyl and chloromethyl; R_7 is

23

selected from the group consisting of C_{1-2} alkyl, chloro- C_{1-2} alkyl, phenyl, 2- and 4-chlorophenyl and 2- and 4-methyl-phenyl; R_8 is selected from the group consisting of C_{1-2} alkyl, C_{1-2} alkylmercapto- C_{1-2} alkyl, phenyl, 2- and 4-chlorophenyl and 2- and 4-methylphenyl; and n is 0-1; with the proviso that at least one of R_7 and R_8 is selected from the group consisting of said phenyl, chlorophenyl and methylphenyl.

4. Ester according to claim 1 wherein n is 0.

5. Ester according to claim 1 wherein such compound is O -(2-bromo-ethyl)- S -methyl- S -phenyl-dithiolphosphoric acid ester of the formula

6. Ester according to claim 1 wherein such compound is O -(2-bromo-ethyl)- S -ethyl- S -phenyl-dithiolphosphoric acid ester of the formula

7. Ester according to claim 1 wherein such compound is O -(2-bromo-ethyl)- S -methyl- S -(4'-chlorophenyl)-dithiolphosphoric acid ester of the formula

8. Ester according to claim 1 wherein such compound is O -(2-bromo-ethyl)- S -ethyl- S -(4'-chlorophenyl)-dithiolphosphoric acid ester of the formula

9. Ester according to claim 1 wherein such compound is O -(2-bromo-ethyl)- S -methyl- S -(2'-methyl-phenyl) dithiolphosphoric acid ester of the formula

10. Ester according to claim 1 wherein such compound is O -(1-bromo-prop-2-yl)- S -methyl- S -phenyl-dithiolphosphoric acid ester of the formula

24

11. Ester according to claim 1 wherein such compound is O -(1-bromo-prop-2-yl)- S -methyl- S -(4'-chlorophenyl)-dithiolphosphoric acid ester of the formula

12. Ester according to claim 1 wherein such compound is O -(4-bromo-but-2-yl)- S -methyl- S -phenyl-dithiolphosphoric acid ester of the formula

13. Ester according to claim 1 wherein such compound is O -(1-bromo-3-chloro-prop-2-yl)- S -methyl- S -phenyl-dithiolphosphoric acid ester of the formula

14. Ester according to claim 1 wherein such compound is O -(1-bromo-but-3-yl)- S -methyl- S -(4'-chlorophenyl)-dithiolphosphoric acid ester of the formula

15. Ester according to claim 1 wherein such compound is O -(1-bromo-prop-2-yl)- S -isopropyl- S -phenyl-dithiolphosphoric acid ester of the formula
